DESIGN FOR A SHOE

William Scott Laurie, Flushing, N. Y.

Application November 7, 1936, Serial No. 65,750

Term of patent 3½ years

To all whom it may concern:

Be it known that I, William Scott Laurie, a subject of the King of Great Britain, residing at Flushing, L. I., county of Queens, and State of New York, have invented a new, original, and ornamental Design for a Shoe, of which the following is a specification, reference being had to the accompanying drawing, forming part thereof.

Fig. 1 is a plan view of a shoe showing my new design.

Fig. 2 is a side elevational view of a shoe as shown in Fig. 1.

I claim:

The ornamental design for a shoe, substantially as shown.

WILLIAM SCOTT LAURIE.
